UNITED STATES PATENT OFFICE.

EDWARD M. GRAHAM, OF CHICAGO, ILLINOIS, ASSIGNOR TO VAUGHAN & BUSHNELL MFG. CO., OF CHICAGO, ILLINOIS, A CORPORATION OF ILLINOIS.

DESIGN FOR A WOOD-CHISEL.

45,527.

Specification for Design.

Patented Mar. 31, 1914.

Application filed February 2, 1914. Serial No. 816,113. Term of patent 14 years.

To all whom it may concern:

Be it known that I, EDWARD M. GRAHAM, a citizen of the United States, residing in the city of Chicago, county of Cook, and State of Illinois, have invented a new, original, and ornamental Design for Wood-Chisels, of which the following is a specification, reference being had to the accompanying drawings, forming part thereof.

In these drawings Figure 1 is a face view of a wood chisel showing my new design;

Fig. 2 is a side view of the chisel shown in Fig. 1; and Fig. 3 is a view of the chisel similar to that of Fig. 1, but showing the reverse side thereof.

I claim:

The ornamental design for a wood chisel, substantially as shown.

EDWARD M. GRAHAM.
